CLAIM

The ornamental design for a transaction card, as shown and described.

DESCRIPTION

FIG. 1 is a perspective view of the transaction card showing our new design;

FIG. 2 is a top view of the design of FIG. 1;

FIG. 3 is a bottom view and of the design of FIG. 1;

FIG. 4 is a first and second side view of the design of FIG. 1; and,

FIG. 5 is a first and second end view of the design of FIG. 1.

The broken lines in the drawings depict portions of the transaction card that form no part of the claimed design.
